APPARATUS FOR BANDING
FILAMENTARY TOWWilliam L. Aspy, Jr., Kingsport, Tenn., assignor to
Eastman Kodak Company, Rochester, N.Y., a corpora-
tion of New Jersey

Filed July 27, 1964, Ser. No. 385,105

1 Claim. (Cl. 19—66)

This invention relates to a wide-slot banding jet. More particularly, it concerns a tow banding jet so constructed as to permit use of air under a reduced pressure to accomplish banding.

U.S. Patent 2,737,688 to Jackson, discloses a box-like tow opening device slotted to permit passage of tow therethrough, said device having a series of openings along the channel through which the tow passes for passage of air under pressure directed from above and below against the tow. While highly satisfactory for banding filter tow, such a jet sometimes requires considerable air pressure to accomplish the desired results. Also, in the Jackson jet to get sufficiently small air openings it is necessary to put together three separate sections, each of which has had a half-opening fabricated therein such that when the three pieces are put together the halves meet to form a whole opening. Therefore, production of a substantially single-piece integral jet which will operate at reduced air pressure represents a highly desirable result. After extended investigation I have found a banding jet, the body of which may be constructed in a single unit such that the air pressure used may be as low as about 1 p.s.i.g.

One object of my invention is to provide a substantially one-piece rectangular banding jet operable at reduced air pressures. Another object is to provide a tow opening device for increased uniformity in banding of tow and improved ease of construction and economy of operation. Further objects will appear hereinafter.

In its broader aspects my invention involves a rectangular banding jet of substantially one piece with a slot therein for passage of tow therethrough and a line of orifices either above or below, to the right or to the left of the tow passage portion, depending on the position in which the jet is operated, whereby air under pressure of as low about 1 p.s.i.g. may be directed through said orifices. The orifices may be as large as about 0.030 inch to band the tow passing through the jet. This enables operation from blowers rather than compressors. I have also found that by using a horn-like or fluted arrangement for directing the air into the jet, it may be distributed more evenly through the openings into the slot through which the tow passes such that increased uniformity and efficiency of banding results. Furthermore, my improved jet is constructed such that the orifices lead only from one direction into the slot or tow opening, thus eliminating the need for a second symmetrical half and further simplifying the structure.

Heretofore, when difficulties sometimes resulted through use of oppositely positioned orifices as small as 0.005 inch with banding air pressures of 3-5 p.s.i.g., concentrating the air at its entrance in a circular or pipe-like channel sometimes tended to prevent adequate distribution of equal amounts of air pressure through the series of orifices above and below the tow passage. As indicated above, I have now found that by increasing the size of the orifices used to around 0.030 inch and using a unidirectional orifice arrangement, I am able to employ air pressures as low as about 1 p.s.i.g. with highly efficient banding of the tow, particularly when a fluted entrance is used for the air or other treating fluid. By increasing the orifice size to as great as 0.028 to 0.032, I permit machining of the sections containing the orifices in one instead of three pieces.

2

Thus the slots may be machined in a single part. Also opposite halves of the circular orifices cannot get out of adjustment.

Although I do not wish to be bound by any particular theory as to why the increase in size of air slots to about 0.030 inch permits lowering of pressure from about 3 or more p.s.i.g. to 1 p.s.i.g. or less, it appears that opening the air slots lowers the required air pressure by removing resistance from the path of the air. This lowering of required air pressure is considerably advantageous whenever facilities limit deliverance of maximum air pressure. As explained above, it is also advantageous in that an integral substantially one-piece banding jet is thus permitted.

For a better understanding of my invention, reference will now be made to the drawing which forms a portion hereof.

In the drawing:

FIG. 1 is a perspective view of a tow opening device constructed in accordance with the present invention.

FIG. 2 is a longitudinal sectional view through the tow opening device of the present invention and taken substantially on line 2—2 of FIG. 1, and showing the relation of the parts; and

FIG. 3 is a transverse sectional view taken through the tow opening device and taken substantially on line 3—3 of FIG. 1.

FIG. 4 is an enlarged perspective view detailing the structure of the orifices of a prior art jet such as that of above-mentioned U.S. Patent 2,737,688.

FIG. 5 is an enlarged perspective view detailing the structure of the orifices of the jet of FIG. 1.

Similar reference numerals throughout the various views indicate the same parts.

In the tow opening device of the present invention, the tow 10, usually pretreated for correct amount of lubricant and crimp, is drawn over a curved guide 11 and then into a thin rectangular slot 12 formed in a separating or opening device, generally indicated by the numeral 13. The latter is in the form of a hollow boxlike member formed with a top cover 14, a bottom portion 15, opposite end walls 16, a back 17 and a front 18. The slot 12 is formed by means of a top cover 14 and orifice containing section 19 of bottom portion 15 as shown in FIGS. 2 and 3. The front wall 18 and back wall 17 are provided with apertures 21 and 22 respectively, which are equal in size to and in alignment with the slot 12, as best shown in FIG. 3. The space 24 between section 19 and remainder of bottom portion 15 provides a plenum chamber which is connected by means of fluted portion 25 and pipe 26 respectively to a suitable source, not shown, of a fluid such as gas under pressure, for example, an air compressor. A suitable take-up mechanism, not shown, such as ball warp or feed rolls of a staple machine controls the rate of speed that the tow 10 is drawn through the device 13 and slot 12 thereof. In order to open the tow 10 to separate the filaments thereof, the tow, while passing through slot 12, is subjected to a fluid pressure, such as compressed air or other suitable gas.

To secure this result, section 19 is provided with a plurality of rectangular orifices 27 of the shape best shown in FIG. 3 and in more detailed form in FIG. 5 to contrast the one-piece structure of the present invention with the multiple structure of the prior art jet of U.S. Patent 2,737,688 as depicted in FIG. 4 hereof. The orifices 27 extend substantially the full width of the section 19 as best shown in FIG. 2. The tapered orifices 27 act as jets to direct the streams of air or other suitable gas under pressure against the moving tow 10 in slot 12 and in a direction perpendicular to the direction of movement of tow 10 in slots 12, as is deemed apparent from an inspection of FIG. 3. While expansion of the air in slot 12, or

upon issuing from slot 12 is inevitable, it is believed that it is the velocity of the air or gas streams impinging on the tow 10 in slot 12 which brings about the separation of the filaments. After the air streams issuing from the orifices 27 impinge perpendicularly on the tow 10 in slot 12, the air then diverges in all directions in the plane in which the tow is moving. Approximately half the air exits or escapes through slot 22 in the back wall 17 and countercurrent to the direction of movement of the tow 10 through the slot 12. The end walls 16 close the ends of the slot 12 and prevent the escape of air from the slot at these points, as is deemed apparent.

For 80,000 denier tow the length of the orifices preferably is 6 inches, while for 5,000,000 denier a length of 25 inches is desirable.

The following examples are illustrative of my invention. These examples are presented in tabular form to show the decreased air pressure required with use of air slots of as large as about 0.030 inch in width.

The following examples show that lower air pressure is required when wider air slots are used. Good banding was obtained in all instances.

4
a front, a thin slot extending substantially the full length and width of the interior of said jet and through which tow is moved, said slot being bound by said top cover, bottom portion, end walls, back and front, said end walls closing the opposite side edges of said slot, said back having formed therein a tow entrance aperture in registry with said slot, said front having formed therein a tow exit aperture in registry with said slot, said apertures extending between said end walls so as to have a width substantially equal to that of said slot, said jet containing a fluid plenum chamber, said bottom portion forming the upper boundary of said plenum chamber, said bottom portion having formed therein fluid openings of a width at least 0.028 inch at the exit ends thereof into said plenum chamber, whereby fluid under low pressure may be supplied to said tow in said slot in a unidirectional perpendicular manner, thereby banding said tow, and means for introducing fluid to said plenum chamber comprising an annular channel leading into the central portion of a flattened funnel-like passage adapted to introduce air to said plenum chamber along substantially its entire width, said hollow box-like jet being constructed as an integral

Ex. No.	Tow	Air Slot Width (Inch)	Tow Passage Width (Inch)	Air Flow, s.c.f.m. ¹	Air Pressure in H ₂ O (Inches)	Air Pressure, p.s.i.g.

¹ Standard cubic feet per minute.

² Denier per filament.

³ Total denier.

From the foregoing description and examples, it is thought apparent that I have provided a jet of improved banding ability, said jet having unidirectional air orifice entrances of a width of about 0.030 inch such that an air pressure as low as about 1 p.s.i.g. or less may be used to efficiently band the tow. By using a horn-type arrangement for entrance of the treating fluid to the jet, I have also provided means for a more even distribution and a more highly uniform banded tow.

This invention has been described in detail with particular reference to preferred embodiments thereof, but it will be understood that variations and modifications can be effected within the spirit and scope of the invention as described hereinabove and as defined in the appended claim.

I claim:

A rectangular hollow box-like jet having a top cover, a bottom portion, opposite parallel end walls, a back and

substantially one-piece unit, the said construction permitting reduced air pressure as low as about 1 p.s.i.g. for effective banding.
